CONTACT MOUNTING FOR ELECTRICAL DEVICES

Douglas H. Loukota and Raymond C. Durant,
Pasadena, and Edward J. Neifing, Los Angeles,
Calif., assignors to James H. Cannon, Los
Angeles, Calif.

Application August 2, 1940, Serial No. 350,015

9 Claims. (Cl. 173—328)

Our invention relates to electrical devices in general, with special reference to contacts for electrically interconnecting conductors, and is directed specifically to an improved method and construction for mounting such a contact in a cooperating insulating support.

While our invention is applicable widely in the electrical art, it is now being incorporated most widely in such connecting fixtures as receptacles and plugs in wall fittings and cable connectors. For the purpose of disclosure, we elect to describe such an embodiment of the invention, but those skilled in the art will readily appreciate that the invention is adaptable to other electrical devices and sufficient guidance will be found herein for applying the invention wherever it may be useful.

A typical receptacle or plug fitting for electric cables and flexible conduit for electric wires comprises a fitting housing, an insulator in the housing, and one or more male or female contacts mounted in the insulator for cooperation with complementary contacts in complementary fittings. In the usual construction the contacts are permanently mounted in the insulator.

One problem that arises in the employment of a conventional fitting is that electric conductors must be soldered to the contacts in making an installation and heat employed in the soldering operation is necessarily conducted through the material of the contact to the insulator in which it is mounted. If a contact is relatively small in diameter, the soldering operation may be performed without any serious heating of the insulator, but if the contact is relatively large the necessary heating of the contact will inevitably damage the insulating body.

Another problem arises when a contact becomes damaged or otherwise unserviceable. The contact in such event must be replaced, and if the contact is mounted in the insulating body in a permanent manner, it becomes necessary to replace not only the damaged contact but also the insulator and all of the other contacts mounted therein. Often the insulator is permanently mounted in the surrounding fitting housing and the fitting housing must also be replaced.

One object of our invention is to provide for detachably mounting a contact in an insulator whereby the contact may be removed at will. It is contemplated that such a contact may be removed from the insulator in a convenient manner for the soldering operation and then remounted after the heat of the soldering opera-

tion is dissipated, thereby avoiding any danger of heat damage to the insulator.

Another object of our invention is to achieve an efficient and positive attachment of a contact to an insulator by relatively simple structure that is inexpensive and readily assembled.

The preferred form of our invention is characterized by the conception of a threaded, or more specifically, a bayonet-type mounting for the contact in the insulator in combination with means to lock the contact against release from engagement with the insulator. One of our more specific objects is to provide such a construction in which the locking means is releasably held in a locking position at which it prevents relative rotation of the contact that is necessary to release the contact from the surrounding insulator. A further object is to provide by a relatively simple structure a groove that is required in either the contact or in the insulator for the bayonet action, and in this regard a feature of our invention is the conception of a laminated insulator, the layers of which are variously apertured to provide such a groove.

25 A still further object of our invention is to maintain a floating mounting for a contact to permit a desirable degree of relative movement on the part of an installed contact.

Other objects and advantages of our invention 30 will be apparent from our detailed description to follow, considered with the accompanying drawings, in which:

Fig. 1 is a side elevation of our invention embodied in a wall plug;

35 Fig. 2 is a longitudinal section through the wall plug of Fig. 1, the wall plug being shown in engagement with a cord receptacle that is partially in section and partially in side elevation;

Fig. 3 is an end view of the wall plug taken 40 as indicated by the arrow 3 in Fig. 2, the detachable contact being removed from the plug;

Fig. 4 shows in perspective the separate laminations of the insulator employed in the wall plug;

45 Fig. 5 is a side elevation of the contact member of the wall plug;

Fig. 6 is an end view of the contact;

Fig. 7 is a perspective view of a locking means that may be employed in the combination;

50 Figs. 8 to 10 are transverse sections taken as indicated by lines 8—8, 9—9, and 10—10 of Fig. 2;

Fig. 11 is a perspective view of a locking means employed in a second embodiment of our invention;

Fig. 12 is a side elevation of a contact member designed for use with the locking means of Fig. 11;

Fig. 13 is an end view of the contact member of Fig. 12 with the locking means of Fig. 11 mounted thereon;

Fig. 14 is a longitudinal section through the assembled second form of our invention, the section being taken on the diameter $x-x$ of Fig. 13; and

Fig. 15 is a similar longitudinal section taken on the diameter $y-y$ of Fig. 13.

The wall plug generally designated 20 in which a preferred form of our invention is incorporated is adapted to be mounted, for example, in a panel or wall member 21 for use in the manner indicated in Fig. 2. The wall plug has a barrel or cylindrical body 22 with a radial flange 23. In the particular installation shown, the barrel 22 is inserted in an aperture 25 in the panel 21 and is held in place by suitable screws 26 through the flange 23. The barrel 22 of the wall plug is adapted to receive telescopically a mating barrel 27 of, for example, a receptacle generally designated 28, the particular receptacle depicted being a connector mounted on the end of a flexible conduit 30. To form interconnection between the wall plug and the receptacle, the barrel 22 of the wall plug may be threaded for engagement by a gland nut 31 that is rotatably mounted on the barrel 27 in engagement with a radial flange 32. Where a waterproof connection is desired, a suitable gasket 33 is usually inserted between the end of the barrel 27 and an annular shoulder 35 in the barrel 22.

Mounted in an insulator generally designated 36 in the barrel 22 of the wall plug is a contact or prong member 37 for electrical cooperation with a complementary contact or receptacle member 38 in the receptacle 28. The present invention pertains to the manner in which the contact 37 is mounted in the insulator 36 and obviously applies to either a prong or receptacle type of contact.

In our invention it is contemplated that either the insulator member 36 or the contact member 37 will have a groove, and the other member will be formed for cooperation with the groove to the end that the contact member may be inserted and rotated in the insulator member for engagement therewith against axial movement, and it is further contemplated that some suitable locking means will be provided to prevent relative rotation of the contact member out of such position of engagement with the insulator member. Preferably the locking means engages one or the other member to prevent the locking means from moving out of its effective position. In the preferred form of our invention we provide for bayonet-type releasable engagement between the contact member and the surrounding insulator, a bayonet groove being provided in the insulator and a complementary shoulder being formed on the contact for cooperation with the groove.

The insulator 36 may be a single body of unitary fabrication, but in the preferred form of our invention the insulator is formed by an assembly of three discs, an inner disc 40, an intermediate disc 41, and an outer disc 42, "outer" here referring to the rear end of the wall plug shown in face view in Fig. 3. The insulator assembly may be secured in the barrel 22 in any suitable manner. In the particular construction shown, the assembly of discs is confined between an annular shoulder 43 in the barrel 22 and a split

ring or "snap wire" 45 of square cross-section that is seated in an annular groove 46. Preferably, the three discs are both keyed to each other and keyed to the barrel 22 by a small cylindrical spline 47 that extends into a complementary semi-cylindrical groove 48 in the barrel and also extends through a complementary notch 50 cut in the margin of each ring. It will be noted that the split ring 45 serves as a keeper for the spline 47 as well as for the assembly of discs. The configurations and functions of the three discs 40-42 may best be explained after referring to the construction of the complementary contact member 37.

The metal contact member 37 has a cylindrical body 51 with an inner face 52 from which a prong portion 53 extends longitudinally. Since a shoulder or other engagement means must be presented by the contact member 37 for engagement with a complementary groove in the insulator assembly, the contact member 37 is provided with at least one radial flange or lug 55, there being two such lugs diametrically opposite each other in the preferred form of the contact. In the manufacture of the particular construction shown in Figs. 5 and 6, the plug is machined to form a radially extending annular flange which is then cut away along the parallel faces 56 to form the two radial lugs 55. The rear end 30 of the contact body 51 forms a cylindrical recess 57 (Fig. 2) which is preferably tinned to facilitate the soldering of a conductor to the contact, Fig. 2 showing a wire 58 so soldered.

The inner disc 40 which rests against the annular shoulder 43 has an aperture 60 dimensioned to receive the prong portion 53 of the contact member 37 so that the face 61 of the disc may abut the face 52 of the contact to limit axial movement of the contact forward through the insulator assembly. The second disc 41 has a larger aperture 62 of sufficient diameter to clear the ends of the two engagement lugs 55. Finally, the outer disc 42 has an aperture 63 of a diameter smaller than the diameter across the lugs 55 but great enough to receive the cylindrical body 51, and diametrically opposite recesses or notches 65 complementary to the lugs 55 are provided in the outer disc to permit the two lugs to be moved past the outer disc into the plane of the intermediate disc 41.

It is apparent from the above description and from reference to Figs. 2, 3, and 4 that the three discs 40-42 cooperate to form an annular groove 66 to which the lugs 55 of the contact member 37 may be admitted through the notches 65. It may be said that the three discs, in effect, form at least one bayonet groove or slot, the axially extending portion of the bayonet slot being provided by one of the notches 65 and the arcuate portion of the slot to permit relative rotation being provided by the annular groove 66. When the contact member is moved axially into the insulator assembly with the two lugs 55 aligned with the notches 65, the lugs are carried into the plane of the intermediate disc 41 and only slight rotation of the contact member relative to the insulator assembly is then necessary to lock the contact member against relative axial movement. The essential fact in the cooperating relationship is that the contact member may be rotated into a position at which a shoulder thereon engages a complementary shoulder of the insulator, and when the combination is viewed in this aspect, it is apparent that each of the lugs 55 forms an engagement shoulder 67 (Fig. 5) to

cooperate with a complementary engagement shoulder 68 (Figs. 2 and 4) formed by the outer disc 42.

While the particular wall plug shown in Fig. 2 has only one contact 37, more often than not such a wall plug has a plurality of prongs of various sizes adapted to cooperate with complementary contacts in complementary receptacles. In practice, it is highly desirable that such numerous prongs mounted in a common insulating assembly be given a certain flexibility of freedom for lateral movement to compensate for minor variations in the spacing and alignment of the contacts. One of the features of the construction shown in the drawings is that we may provide any required degree of such tolerance by making the contact-receiving apertures of the three discs 40-42 somewhat oversize relative to the contact member 37 and by making the intermediate disc 41 somewhat oversize in thickness relative to the thickness of the two lugs 55, thereby achieving what may be called a "floatingly mounted contact".

The locking means contemplated in our invention to prevent rotation of the contact member out of the bayonet engagement with the insulator assembly is preferably releasably engaged with the contact member for maintenance in its effective position. In the particular construction shown in the drawings we provide a latching shoulder 70 on the contact member 37 by cutting a circumferential groove 71 in the cylindrical body 51 and employ for our locking means a simple metal clip generally designated 72 in Fig. 7. The locking clip 72 comprises a resilient split ring portion 75 and integral therewith a key portion 76 dimensioned to fit longitudinally into one of the notches 65 in the outer disc 42.

After the contact member 37 is inserted in the insulator assembly and rotated to carry the lugs 55 out of alignment with the notches 65, the clip 72 may be slipped onto the cylindrical body 51 of the contact member with the key portion 76 extending through one of the notches 65 into the plane of the intermediate disc 41. At the effective position of the clip 72 the split ring portion 75 embraces the contact body 51 in the circumferential groove 71 and is thereby retained against accidental removal. Release of the contact member while the key 76 is in its effective position is prevented because rotation of the contact member in either rotary direction is stopped by abutment of one of the lugs 55 with the key portion, the key portion being anchored against rotation by abutment against an edge of the outer disc 42 at the particular notch 65 in which the key extends. The locking clip 72 may, of course, be removed when desired by simply springing the split ring portion 75 out of the circumferential groove 71 and slipping the clip axially off the cylindrical body 51 of the contact member.

It is apparent from the foregoing description that the contact member 37 may be mounted and dismounted from the insulator 36 at will. In the procedure of installing such an electrical fitting in some particular electric circuit, the contact member is temporarily removed from the insulator for the soldering operation and is replaced after the contact member cools sufficiently to avoid any possible damage to the insulator. After a period of service in the given installation, the contact member may be removed for replacement, if necessary, or may be removed

in the described manner for mounting the wire 58 in some other electrical fitting of similar construction.

The second embodiment of our invention illustrated by Figs. 11 to 15 is similar to the first embodiment described above except that the locking clip 85 of Fig. 11 is substituted for the locking clip 72 of Fig. 7, and the contact member 87 of Fig. 12 may be substituted for the contact member 37 of Fig. 5. Other parts of the device are unchanged and in Figs. 14 and 15 are designated by the same numerals as heretofore employed.

The new locking clip 85 has two key portions 15 or locking tongues 88 disposed diametrically opposite from each other to enter the two notches or recesses 65 of the insulating member 36. The ends 90 of the locking tongues 88 are deformed or bent for releasable engagement with the contact member 87 so that the two tongues not only serve to lock the assembled contact member against rotation, but also serve to anchor the locking clip.

The contact member 87 is similar to the previously described member 37, but lacks a circumferential groove since such a groove is not necessary for retaining the locking clip 85. The contact member 87 has a cylindrical body 91 with an inner face 92 from which extends a prong portion 93, and the contact member has two radial flanges or lugs 95 to cooperate with the insulating body 36 in the manner previously described. The rear end of the contact body 91 forms the usual cylindrical recess 97.

The second embodiment of our invention is assembled in much the same manner as the first embodiment. The contact member 87 is inserted in the insulator assembly and rotated to carry the lugs 95 out of alignment with the notches 65 of the insulator 36. The locking clip 85 is then slipped onto the cylindrical body 91 and shifted along the contact member until the end portions of the locking tongues 88 snap into engagement with the contact member at the inner face 92, as best shown in Figs. 13 and 15. The locking clip 85 may be removed at will by applying sufficient force longitudinally to dislodge the ends 90 of the locking tongues 88. One feature of this form of our invention is that when the locking clip 85 is in assembled disposition, it is exposed sufficiently to permit the use of a screw driver as a pry to force the locking clip out of engagement with the contact member 87. Fig. 15, for example, shows in dotted lines a screw driver 100 disposed at an angle for insertion into the assembly to pry the locking clip 85 rearward.

It will be apparent to those skilled in the art that the present detailed disclosure exemplifies a number of diverse arrangements based on the same inventive concept, and we specifically reserve the right to all such forms of our invention that come within the terms of our appended claims.

We claim as our invention:

1. In an electrical connecting fitting movable into and out of engagement with a complementary connecting fitting, the combination of: an insulating member having a longitudinal passage extending completely therethrough, said member having a rearwardly presented stop surface adjacent said passage, a portion of said passage in the rearward end thereof forming a longitudinal bayonet groove and a locking recess; a contact member extending through said passage with a portion projecting forward from

the passage for electrical contact with said complementary fitting, said contact member having a forwardly presented stop surface for abutment with said rearwardly presented stop surface to limit forward extension of said projecting portion of the contact member, said contact member having a peripheral bayonet projection for assembly movement through said groove into normal locking position in said recess; and locking means normally extending along said contact member through said groove to block unlocking movement of said bayonet projection, said locking means releasably engaging one of said members to prevent accidental retraction of the locking means.

2. In an electrical connecting fitting movable into and out of engagement with a complementary connecting fitting, the combination of: an insulating member having a longitudinal passage extending completely therethrough, said member having a rearwardly presented stop surface adjacent said passage, a portion of said passage in the rearward end thereof forming a longitudinal bayonet groove and a locking recess; a contact member extending through said passage with a portion projecting forward from the passage for electrical contact with said complementary fitting, said contact member having a forwardly presented stop surface for abutment with said rearwardly presented stop surface to limit forward extension of said projecting portion of the contact member, said contact member having a peripheral bayonet projection for assembly movement through said groove into normal locking position in said recess; and locking means extending into said groove to block unlocking movement of said bayonet projection, said locking means being radially flexible for movement into and out of releasable engagement with one of said members to prevent accidental retraction from said groove.

3. A combination as set forth in claim 2 in which one of said members has an annular recess with a rearward wall and in which said locking member normally engages said member in said recess, whereby said rearward wall prevents outward retraction of the locking means from said groove.

4. In an electrical connecting fitting movable into and out of engagement with a complementary connecting fitting, the combination of: an insulating member having a longitudinal passage extending completely therethrough, said member having a rearwardly presented stop surface adjacent said passage, a portion of said passage in the rearward end thereof forming a longitudinal bayonet groove and a locking recess; a contact member extending through said passage with a portion extending rearwardly from said passage and a portion projecting forward from said passage for electrical contact with said complementary fitting, said contact member having a forwardly presented stop surface for abutment with said rearwardly presented stop surface to limit forward extension of said projecting portion of the contact member, said contact member having a peripheral bayonet projection for assembly movement through said groove into normal locking position in said recess; and a locking means extending into said groove to block unlocking movement of said bayonet projection, said locking means normally yieldingly embracing said contact member adjacent said forwardly presented shoulder to prevent accidental retraction of the locking means from said groove. 75

5. In an electrical connecting fitting movable into and out of engagement with a complementary connecting fitting, the combination of: an insulating member having a longitudinal passage extending completely therethrough, said member having a rearwardly presented stop surface adjacent said passage, a portion of said passage in the rearward end thereof forming a longitudinal bayonet groove and a locking recess; 10 a contact member extending through said passage with a portion extending rearwardly from said passage and a portion projecting forwardly from said passage for electrical contact with said complementary fitting, said contact member having a forwardly presented stop surface for abutment with said rearwardly presented stop surface to limit forward extension of said projecting portion of the contact member, said contact member having a peripheral bayonet projection for assembly movement through said groove into normal locking position in said recess, said contact member having a peripheral recess in said rearwardly extending portion; and locking means extending into said groove to block unlocking 20 movement of said bayonet projection, said locking means yieldingly embracing said contact member in engagement with said peripheral recess to prevent accidental retraction of the locking means from said groove.
6. In an electrical connecting fitting movable into and out of engagement with a complementary connecting fitting, the combination of: an insulating member having a longitudinal passage extending completely therethrough, said member having a rearwardly presented stop surface adjacent said passage, a portion of said passage in the rearward end thereof forming a longitudinal bayonet groove and a locking recess; a contact member extending through said passage with a portion projecting forward from the passage for electrical contact with said complementary fitting, said contact member having a forwardly presented stop surface for abutment with said rearwardly presented stop surface to limit forward extension of said projecting portion of the contact member, said contact member having a peripheral bayonet projection for assembly movement through said groove into normal locking position in said recess; and locking 30 means for preventing unlocking movement of said bayonet projection, said locking means comprising a flexible split ring normally engaged with one of said members and a projection extending forward from said split ring into said groove.
7. In an electrical connecting fitting movable into and out of engagement with a complementary connecting fitting, the combination of: an insulating member having a longitudinal passage extending completely therethrough, the rearward portion of said passage being of non-circular cross section, an intermediate portion of said passage forming a locking recess, the portion of the passage forward of said recess being of smaller cross-sectional dimension than said rearward portion of the passage; a contact member extending through said passage with a portion projecting forward from the insulating body for electrical contact with said complementary fitting, said contact member having a peripheral bayonet projection normally extending in locking position into said locking recess, the cross-sectional dimension of the contact member at said bayonet projection being greater than the cross-sectional dimension of said forward portion of the passage; and locking means extend- 40 45 50 55 60 65 70

ing through said insulating member to block unlocking movement of said bayonet projection, said locking means being releasably engaged with one of said members to prevent retraction of the locking means.

8. In an electrical connecting fitting movable into and out of engagement with a complementary connecting fitting, the combination of: an insulating member having a longitudinal passage extending completely therethrough, the rearward portion of said passage being of non-circular cross section, an intermediate portion of said passage forming a locking recess, the portion of the passage forward of said recess being of smaller cross-sectional dimension than said rearward portion of the passage; a contact member extending through said passage with a portion projecting forward from the insulating body for electrical contact with said complementary fitting, said contact member having a peripheral bayonet projecting normally extending in locking position into said locking recess, the cross-sectional

dimension of the contact member at said bayonet projection being greater than the cross-sectional dimension of said forward portion of the passage; and locking means normally extending into said insulating member to block unlocking movement of said bayonet projection, said locking means having a flexible split-ring portion for releasable engagement with one of said members, said split-ring portion being yieldable to clear 10 said contact member for lateral removal of the locking means.

9. A combination as set forth in claim 7 in which said insulating member comprises an assembly of at least three bodies, one body being apertured to form said forward portion of said passage, one body being apertured to form said locking recess, and one body being apertured to form said rearward portion of said passage.
